DESIGN FOR A RADIO DIAL ESCUTCHEON PLATE

William E. Salyards, Jr., Highland Park, Ill., assignor to Crowe Name Plate & Manufacturing Co., Chicago, Ill., a corporation of Illinois

Application September 18, 1936, Serial No. 64,921

Term of patent 3½ years

To all whom it may concern:

Be it known that I, William E. Salyards, Jr., a citizen of the United States, residing at Highland Park, county of Lake, and State of Illinois, have invented a new, original, and ornamental Design for a Radio Dial Escutcheon Plate, of which the following is a specification, reference being had to the accompanying drawing, forming a part hereof:

Fig. 1 is a view in front elevation of a radio dial escutcheon plate showing my new design; and

Fig. 2, a section taken at the line 2 on Fig. 1 and viewed in the direction of the arrow.

I claim:

The ornamental design for a radio dial escutcheon plate, as shown.
